COLLAPSIBLE CRANE OR PLATFORM TOWER

Valentine Gerich, New York, N. Y.

Application June 28, 1943, Serial No. 492,638

5 Claims.

(Cl. 212—55)

This invention relates to a telescopic and collapsible apparatus, particularly to an extension crane-hoist of a toggle formation for use in construction work of erecting buildings of medium height, and is also adaptable for use as life saving tower in burning buildings.

The main object of this invention, is the progressive arrangement of the toggle beams, that are extendable instantly by a power driven screw-rod operable on a turntable mounted upon a chassis or frame of a truck, caterpillar or upon the ground. The extendable beams are instantly collapsible by reversing the extendable operation, in which all of the beams fold themselves within each other.

Another feature of this invention, is the crane or boom part of the crane-hoist, which is adaptable to hoist light and heavy work, controllable by cables and power driven winches operated at the base of the apparatus.

Another feature of this invention, is the adaptation of utilizing the top portion of the toggle beams for mounting thereon a water nozzle of a fire tower apparatus.

Another feature of this invention, is the adaptation of mounting a cage or box-like car on the top portion of the toggle beams, which is so arranged the toggle arms supporting the car are slideable underneath, in their inwardly and outwardly movement during the extendable and collapsible operations of the crane-hoist.

A further feature of this invention, is the adaptability of using the toggle crane-hoist as an amusement park attraction, in which a possible height of several hundred feet may be the extendable observation position, the tower being rotatable, so the passengers in the car may look in all directions.

A further feature of this invention, is its use for a lookout tower for the armed forces, and also for a search-light, and for a crow-nest tower on warships.

Other features of this invention will appear as the description proceeds in the following specification, in which

Figure 1 shows a side elevational view of the telescopic crane-hoist in its extendable position.

Figure 2 is an end view of the same Figure 1.

Figure 3 shows the top portion of the toggle beams provided with cage or box-like car, for use as part of fire life saving apparatus, or as an amusement park attraction.

Figure 4 shows a similar view, except a fire water nozzle is mounted in place of the cage or box-like car.

Figure 5 shows the toggle beams collapsible from the extended position as shown in Figure 1.

Figure 6 shows diagrammatically toggle beams having the same length.

Referring to the drawings, the numeral 1 indicates the complete crane-hoist apparatus, having toggle beams in pairs 1—1; 2—2; 3—3; 4—4; 5—5; 6—6; all of which are pivoted together at 1—7 and 8—8. These toggle beams are so set and arranged progressively that the top beams 6—6 are about one-half the length of the lowermost base beams 1—1 operable on the turntable platform P, thus providing a pyramid construction.

15 The top arms 9—9 pivoted to the beams 6—6, have a boom or hoisting bell-crank shape member 10 mounted onto the tubing shaft 11h therewith, the boom 10 having pulleys 12 and 13 for cables 14 and 15 connecting to pulleys 16 and 17 on shaft 11h thence to the winches 19 and 20, respectively, which are power driven by the motors M1 and M2 adjacent the base of the crane-hoist. The boom itself is operated by the cable 23 secured at 24 to the end of the short arm 25 of the boom 10, the cable connecting to a pulley 26 outside the turntable and adjacent the lowermost toggle beams 1—1 thence upwardly to the pulley 27 on the short arm 25 and thence down to the winch 28 which is power driven by a motor 30 M3.

20 The toggle beams 1—1, 2—2, 3—3, 4—4, 5—5 and 6—6 are spaced and retained apart by tubing spacers or shafts 11a, 11b, 11c, 11d, 11e and 11f, respectively, and the end portions of beams are 25 similarly connected by tubing shafts 7a and 8a. As noted in Figure 2 the beams are progressively set within each other inwardly so as to form a brace-like or pyramid assembly when they are extended as shown in Figures 1 and 2. The toggle beams may be made otherwise than shown, but it is believed that the beams shown are suitable for side strains or thrusts. However, the toggle beams from the uppermost beams 9, down to the lowermost beams 1, and including the intermediate beams 2, 3, 4, 5 and 6, may be all of 30 the same length if so desired.

25 The cable 14 has a light duty hook 14a, and the cable 15 has a heavy duty hook 15a and doubled wound cable arrangement as shown, and the boom 10 may be of any suitable length, hence the broken portions of each short and long arm thereof.

The lowermost toggle beams 1—1 are pivoted to the blocks 30 and 31, which are operable by 35 the rotatable right and left threaded shafts or

rods or rod portions 32 and 33, respectively. The threaded shafts or portions are operated by a motor M4 of the reversible type, or by separate motors, if so desired, by means of a worm 34 and worm wheel 34a. The screw rods are mounted onto a bed-plate or frame member 35 in bearings 36 and 37, the frame member being rotatable on rollers 39, thus providing a turntable in which a king bolt 40 secures them together pivotally to the frame platform P of the caterpillar C shown in dot and dash lines, which may be a large tractor or truck, if so desired.

In Figure 2, it will be noted that the toggle beams are adapted to be collapsible within each other as shown in Figure 5, and suitable means not shown may be provided for taking up the slack of the cables during the collapsible operation, and for the pull during the extending operation of the crane-hoist I.

The operation controls may be arranged within in a cab C or outside of the turntable, in which means will be provided for the rotatable movement for the cables, but as it is now shown the cables 14 and 15 have their winches and motor drive within the beams and upon the turntable platform P, and the cable 23 is outside thereof.

In Figure 3, a box-like car 45 is arranged in fixed bearings 46, 47 and 48 on each side portions of the car, rods 50 being secured therein, onto which is slidably blocks 51 and 52 pivoted to the end of the upper toggle beams 6-6. A center bar 55 extending through a fixed bearing 56 on each side of the car, provide means to retain car in a normal neutral position, so the beams 6-6 means open and close with the blocks 51 and 52 accordingly. An extendable gangway bridge member 60 may or may not be part of the car, for use between car and building B all shown in dot-dash lines in Figure 3. The car may be interchangeable with a water gun or nozzle 65 shown in Figure 4, or either may be permanently arranged as shown.

When the extended toggle beams are used for an amusement device, the base may be spread over a plot of about 50 feet square, more or less, and anchor cables may be added for safety from wind or gales. However, this toggle arrangement is instantly collapsible within a two or three seconds for emergencies. An altitude of 300 to 500 feet is possible with this crane-hoist comprising toggle beams, and the observation car may hold thirty people, and when the device is extended to higher position it may be rotated around at least once, or more, if so desired.

Having thus described my invention, what I claim as new and to secure by Letters Patent of the United States of America, is as follows:

1. In a collapsible crane apparatus of the character described, including a plurality of toggle beams arranged in pairs and spaced apart and connectably secured together pivotally at their center and end portions, said toggle beams spaced apart by tubing members mounted onto tie-rods that extend through said toggle beams which are pivotally secured onto the ends of said tie-rods by lock-nuts, thereby holding all of said toggle

beams rigidly in their pivoted positions, the lowermost toggle beams securely mounted onto a turntable member, and the uppermost toggle beams adapted to support a platform, which may be interchangeable with a box-like car, or a crane hoisting boom, means to operate said lower toggle beams for extending all of said toggle beams to any desired height, and further means to lower said toggle beams to their collapsible and normal positions.

2. In a collapsible crane apparatus and platform tower of the character described, including a plurality of toggle beams arranged in pairs suitably spaced apart and connectable at the center and end portions by tubing spacers all of which are tied together by tie-rods and lock-nuts therewith, the lowermost toggle beams securely mounted onto a rotatable platform, the uppermost toggle beams supporting a bell-crank boom, the boom end provided with pulleys for cables with hoist hooks at their ends thereof, said bell-crank boom operative by suitable power means adjacent said lower platform, further means to extend all of said toggle beams in their extendable positions to any desired height, and further means to lower said toggle beams to a collapsible position onto said lower platform, and said bell-crank boom adaptable for being interchangeable for a box-like car, or a water nozzle platform, is so desired.

3. In a collapsible tower platform of the character described, including a plurality of toggle beams of not less than six sections arranged in pairs, each pair and section spaced apart by tubing and tie-rods with lock-nuts at their center and end portions, the lowermost toggle beams adapted to be mounted onto a suitable platform, the uppermost toggle beams adapted to support either a box-like car, or an open platform, or a bell-crank boom, all of which are interchangeable with each other onto said uppermost toggle beams, said toggle beams adapted to be extended to any desired height and to be collapsible to their lowermost positions, said toggle beams may be of sufficient number of sections whereby said uppermost toggle beams may be extended to a height of 100 feet or more, and when of much greater height, may be braced by tie cables in any direction therefrom.

4. In a collapsible tower platform of the character described, and as defined in claim 4, said uppermost toggle beams when supporting a box-like car, provides an amusement device or toy-like device, whereby said toggle beams are constructed in proportion therewith, and when the bell-crank boom is used, the same proportions are maintained for their respective purposes as hoisting crane apparatus or a toy-like device.

5. In a collapsible tower platform apparatus of the character described, and as defined in claim 4, said uppermost toggle beams provided with a center bar that is slidable in bearing of part being supported thereon, whereby said part may be held in a neutral and certain position during the extending and collapsing of said toggle beams.

VALENTINE GERICH.
